UNITED STATES PATENT OFFICE.

WILLIAM J. SMITH, OF DENVER, COLORADO.

DESIGN FOR A SUPERSERVICE-FLAG.

55,537.

Specification for Design. Patented June 22, 1920.

Application filed May 31, 1918. Serial No. 237,646. Term of patent 3½ years.

To all whom it may concern:

Be it known that I, WILLIAM J. SMITH, a citizen of the United States, residing at the city and county of Denver and State of Colorado, have invented a new, original, and ornamental Design for a Superservice-Flag, of which the following is a specification, reference being had to the accompanying drawing, forming a part thereof.

This article is a super-service flag, com-

prising a red background with a white center carrying a gold star, the background having a blue border.

The figure is a front view of the flag showing my new design.

I claim:

The ornamental design for a superservice flag as shown.

In testimony whereof I affix my signature.

WILLIAM J. SMITH.
